UNITED STATES PATENT OFFICE.

MORRIS J. NEWMAN AND MICHELE IANNETTI, OF BROOKLYN, NEW YORK.

BED.

Application filed December 19, 1921, Serial No. 523,334. Renewed February 8, 1923.

To all whom it may concern:

Be it known that MORRIS J. NEWMAN and MICHELE IANNETTI, both citizens of the United States, residing at the city of New York, borough of Brooklyn, in the county of Kings and State of New York, have invented certain new and useful Improvements in Beds, of which the following is a specification.

10 This invention relates to beds. More particularly it is directed to a child's bed or crib wherein provision is made for the raising and lowering of a side to facilitate the placing of the occupant into the crib or 15 moving the child therefrom when desired.

One object thereof is to provide in a crib of this character means for lowering and raising a side thereof which means shall be inaccessible to the occupant, proof against 20 being tampered with and thus adapted to prevent accidental falling of the child out of the crib.

Another object is to provide a device of the character described which shall be simple 25 in construction, and easy to manipulate, comparatively inexpensive to manufacture and efficient in operation to a high degree.

Other objects of this invention will in part 30 be obvious and in part hereinafter pointed out.

The invention accordingly consists in the features of construction, combinations of elements and arrangement of parts which will be exemplified in the construction herein- 35 after described and of which the scope of application will be indicated in the following claims.

In the accompanying drawings, in which 40 is shown one of various possible illustrative embodiments of this invention,

Fig. 1 is a side elevation of a crib, embodying and containing the invention;

Fig. 2 is a fragmentary view showing in 45 vertical section the locking mechanism and the portions of the crib to which the parts are secured;

Fig. 3 is a detail section of the locking mechanism taken along line 3—3 of Fig. 1;

Fig. 4 is a detail section cut along line 50 4—4 of Fig. 2.

Referring in detail to the drawing, there is illustrated in Fig. 1 a child's crib 10 having a vertically slidable side 11 adapted to be lowered into position such as shown in 55 dotted lines in Fig. 1 so as to make the interior of the crib readily accessible for

placing a child therein or removing it therefrom.

Means are provided for automatically and releasably locking the slidable side 11 in closed position. To this end a bracket 12 is secured to the lower rail 13 of the side 11. Preferably the bracket 12 is provided with a flat flange 14 extending at right angles thereto and a screw or rivet 15 or other suitable fastening member passes through the flange and the rail 13 so as to secure the bracket rigidly in position. Formed integral with the bracket 12 is a trip member 16 having a flat bottom face 17 and a cut away side so as to form a cam face 18 for the purpose hereinafter described.

An angle bar 19 is secured to a pair of side posts 20, 20' of the crib, and secured to one face 21 thereof by means such as screws or other fastening members 22 is an open lock casing 23, the other face 24 of the angle serving to enclose between it and the flat face 25 of the casing a guide within which slides a lock bolt member 26. This bolt member is provided with a longitudinal slot 27 within which lies a spring 28 having one end secured to a pin 29 extending from the inner wall of the face 25 into the slot and the other end secured to rear wall of the slot as at 30. The bolt member is formed at the rear with a flat integral stop member 31, and at the front end with a trip portion 32 having a flat top face 33 on which normally rests the corresponding bottom face 34 of the trip member 16. The trip portion 32 has the front side thereof cut away so as to form a cam face 34 corresponding to the cam face 18 but cut in the reverse direction as will appear from Fig. 2. Extending from the rear portion of the slidable lock bolt 26 is an ear member 35 to which is pivoted a vertical latch bar 37 having an operating portion 38, adapted to be foot-manipulated. The upper portion 37^a of the latch bar extending above the pivotal point is adapted to act against the rear wall 39 of the casing so as to force the slide bolt to move inward and away from the trip member 16.

The operation of the device will now be clear. In the normal closed position (that is raised position) of the slidable side 11, the trip member 16 rests on the trip portion 32 with their respective bottom and top faces 110 abutting each other. If it is desired to lower the side 11, the operating portion 38

is pushed to the side by means of the foot, when the latch bar 37 is moved against the action of the spring thus causing the lock bolt 26 to be withdrawn into the casing. 5 The trip portion 32 will then have moved away from the trip member 16 and the bracket 12, thus released will drop under the influence of its own weight carrying with it the slideable side 11. The relation of 10 the parts in this open position of the crib is shown in dotted lines in Fig. 2. In restoring the side 11 to normal closed position, it is simply pushed up manually and as the cam face 18 moves upward it rides on 15 and acts against the reverse cam face 34, thus forcing the lock bolt 26 in against the spring 28 and just as the bottom of the cam face 18 passes the top of the cam face 34, the restoring action of the spring forces 20 the trip portion 32 out to be positioned under the trip member 16 thus automatically locking the side 11 in closed position. It will be noted that the operating handle or latch bar 37 is completely on the outside of 25 the crib, far removed from the occupant and operable practically only from the outside of the crib.

It will thus be seen that there is provided 30 a device in which the several objects of this invention are achieved and which is well adapted to meet the conditions of practical use.

As various possible embodiments might be made of the above invention and as various 35 changes might be made in the embodiment above set forth, it is to be understood that all matter herein set forth or shown in the accompanying drawings is to be interpreted as illustrative and not in a limiting sense.

Having thus described our invention, we 40 claim as new and desire to secure by Letters Patent:

1. A crib provided with a pair of side posts and a vertically movable side railing, 45 a bracket extending downwardly from said side railing, a trip member extending from said bracket and having a cut away portion, a support between the said end posts, a lock secured to said support for releasably sup- 50 porting said trip member, said lock comprising a lock bolt and a spring operatively secured thereto, said lock-bolt having a cut- away portion adapted to co-act with the corresponding cut-away portion of the trip member for retracting the lock bolt upon 55 raising the side railing.

2. A crib provided with a pair of side posts and a vertically movable side railing, a bracket extending downwardly from said 60 side railing, a trip member having a cut- away portion carried by said bracket, a sup- port between said end posts, a lock secured to said support, said lock comprising a cas- ing, a lock bolt having a cut-away portion

adapted to co-act with the corresponding 65 cut-away portion of the trip member for releasably supporting said trip member, said lock bolt having a slot formed therein and provided with an opening adjacent one 70 end of said slot, a pin formed in the casing adjacent the other end of said slot, a spring disposed within said slot with the ends thereof secured within the opening and to the pin, and a latch bar pivotally secured to said lock bolt for releasing the trip 75 member.

3. A crib provided with a pair of side posts, and a vertically movable side railing, a bracket extending downwardly from said side railing, a trip member carried by said bracket, a support maintained between said end posts, a lock secured to said support, said lock comprising a casing open at the rear thereof and disposed on the support 80 so as to form a channel, a lock bolt adapted to be reciprocated within said channel, said lock bolt having a slot formed therein and provided with an opening adjacent one end of said slot, a pin formed in the casing adjacent the other end of said slot, a spring disposed within said slot with the ends thereof secured within the opening and to the pin and a latch bar pivotally secured to said lock bolt for releasing the trip member. 85

4. In a crib, in combination with a movable side member for opening and closing the same, and in combination with a horizontal support disposed on the lower portion of the said crib on the movable side thereof, a locking device for automatically 100 locking the said side member, said locking device comprising a bracket member secured to said side member and having a vertically cut away trip member extending therefrom and disposed with its lower face 105 substantially horizontal and its cut away portion inclined and adapted to act as a cam face, and means secured to said horizontal support for normally supporting the said bracket member adjacent the lower horizontal trip member face thereof, said means comprising a casing member secured to said horizontal support and adapted to slidably hold therebetween a bolt member, having a trip member extending from one end 110 thereof adapted to co-act with said afore- mentioned trip member, a spring member within said casing and adapted to normally hold said bolt member so that the said trip members abut each other, and a latch mem- 115 ber pivoted to the free end of said bolt mem- ber for removing the latter from under the bracket member. 120

In testimony whereof we affix our signatures.

MORRIS J. NEWMAN.
MICHELE IANNETTI.
